UNITED STATES PATENT OFFICE.

ANDREW E. MILLER, OF BALTIMORE, MARYLAND, ASSIGNOR TO SOLOMON HIMMEL, OF BALTIMORE, MARYLAND.

DISPLAY-RACK.

1,176,717.

Specification of Letters Patent. Patented Mar. 21, 1916.

Application filed August 21, 1913. Serial No. 785,892.

To all whom it may concern:

Be it known that I, ANDREW E. MILLER, a subject of the King of Great Britain, residing at Baltimore, in the State of Maryland, have invented new and useful Improvements in Display-Racks, of which the following is a specification.

This invention relates to an improvement in display racks for garments and the like.

10 It is now common practice to mount a rotatable rack upon a suitable carriage or other support, arranged to move back and forth within an inclosing casing. The major portion of the casing is usually constructed of glass, and if the garment supporting bars of the rack are not placed in proper alinement with the back of the case, before being pushed back thereinto, there is danger of breaking or cracking the glass. I 15 have found, however, in practice, that the weight of the garments or the like upon the rack is such that ordinarily the rack will not be rotated in its rearward movement, if it is first brought into proper alinement.

20 The object of the present invention is to provide means for preventing rearward movement of the rack and its carrier until the garment supporting bars have been brought to a position parallel with the rear 25 wall of the case.

A further object is to provide means for locking the carriage in the forward position irrespective of the angular position of the rack supporting bars with respect to the rear 30 wall of the case, said locking means becoming effective immediately upon the arrival of the carriage to the forward position.

35 A further object is to provide means for disengaging the lock by a rearward movement of the carriage when the garment supporting bars are in proper alinement with the walls of the case.

The invention will be hereinafter fully set forth, and particularly pointed out in 40 the claims.

In the accompanying drawing:—Figure 1 is a plan view illustrating my invention, portions of the case being broken away. Fig. 2 is a sectional view on the line 2—2 of 45 Fig. 1. Fig. 3 is a similar view illustrating the locking of the parts during the rotation of the rack. Fig. 4 is a similar view illustrating the means for disengaging the lock.

50 Referring to the drawing, 10 designates a case of any suitable or preferred construc-

tion, the bottom of which is provided with a chamber or channel 12, the upper edges of which are provided with guides 13 between which the carriage 14 is mounted to reciprocate. Said carriage is provided with a 60 tubular bearing 15 in which is rotatably mounted a shaft 16 which is designed to support the garment supporting bars or rods usually employed in display racks of this type, and which are not here illustrated. Secured to the shaft 16 is a disk 17 provided with notches 18 to receive a roller 19 carried by a lever 20 pivoted to the carriage at 21, said roller being held normally in engagement with the periphery of the disk 17 by a spring 22. The relative arrangement of the notches 18 and roller 19 is such that said roller tends to hold the disk 17 and shaft 16 against rotation, the 65 spring 22 yielding to permit the roller 19 to ride out of the notch 18 when suitable pressure is applied to the shaft 16, tending to rotate the same. These notches are also so shaped that as the roller 19 engages either 70 of them the disk 17 is centered so as to hold the garment supporting bars (not shown) in proper alinement with the walls of the 75 case.

Pivottally mounted in suitable bearings 25 supported in the channel or chamber 12 80 near the forward edge of the case is a locking member 26 provided with a shoulder 27 and a rearwardly extended off set portion 28 provided with an upstanding lug 29. A 85 spring 30 tends to hold said locking member 26 in a normally upward position. The off set portion 28 and the shouldered portion 27 are connected by an inclined cam surface 31.

The carriage 14 is provided with a depending lug 32 arranged to coöperate with the detent or locking member 26. The disk 17 is also provided with oppositely disposed depending lugs 33 arranged to engage the lug 29 on the detent or locking member 26. 90

In practice as the carriage is moved from the rearward position within the case to the forward position illustrated in Fig. 1, the lug 32 will engage the cam portion 31 of the detent 26 and depress the same in opposition to the spring, until said lug passes the shoulder 27. As the lug passes said shoulder, one of the lugs 33 on disk 17 engages the lug 29 and holds the detent depressed until the parts reach the position 100 105 110

illustrated in Fig. 2. When the shaft 16 and the disk 17 are rotated the forward member 33 moves away from the lug 29 as illustrated in Fig. 3, whereupon the 5 detent 26 will coöperate with the lug 32 to interrupt rearward movement of the carriage. This rearward movement, except to a slight extent, is prevented during the entire rotation of the rack, or as long as the 10 garment supporting bars of the latter are out of alinement with the walls of the case. As soon as the garment supporting bars are brought into proper alinement, the parts again assume the positions illustrated in 15 Fig. 2, the roller 19 and the notches 18 tending to automatically right the disk to this position. When the parts are in the positions illustrated in Fig. 2 the slight rearward movement of the carriage that is permitted, causes the lug 33 to engage the lug 29 and depress the detent sufficiently to permit the shoulder 27 to clear the lug 32, whereupon the carriage may continue its rearward movement without impediment. 25 It will be noted that the lug 32 is spaced sufficiently from the shoulder 27 to permit the necessary preliminary rearward movement for effecting the unlocking of the carriage.

30 Having thus explained the nature of my invention and described an operative manner of constructing and using the same, although without attempting to set forth all of the forms in which it may be made, or 35 all of the forms of its use, what I claim is:—

1. As an improvement in display racks, a reciprocable carriage, a rotatable rack supported thereby, means for interrupting reciprocation of said carriage, said means being located near one extremity of the movement of the carriage, and means attached to and movable with the rack and actuated by a movement of the carriage in one direction for disengaging said carriage from said interrupting means, said disengaging means being operable at predetermined points in the rotative movement of the rack. 40

2. As an improvement in display racks, a reciprocable carriage, a rotatable rack member supported thereby, means for interrupting reciprocation of said carriage, said means being located near one extremity of the movement of the carriage, and means operated by a rearward movement of the carriage for disengaging the latter from said interrupting means, said disengaging means being operable at predetermined points in the rotative movement of the rack. 45

3. As an improvement in display racks, a 50 carriage, a base in which said carriage is mounted to reciprocate, a detent pivoted to said base to interrupt reciprocable movement of the carriage near one extremity of its movement, and means operated by a return movement of the carriage for disengag-

ing the latter from said detent, said disengaging means being operable when the rack is at predetermined points in its rotative movement.

4. As an improvement in display racks, a reciprocable carriage, a rotatable rack supported thereby, means for interrupting reciprocation of said carriage, said means being located near one extremity of the movement of the carriage, means connected with the rack and operated by movement of the carriage in one direction for disengaging said carriage from said interrupting means, said disengaging means being operable at 75 predetermined points in the rotative movement of the rack, and means for causing said rack member to assume a predetermined position to render said disengaging means operative. 80

5. As an improvement in display racks, a carriage, a base in which said carriage is mounted to reciprocate, a detent pivoted to said base to interrupt reciprocable movement of the carriage near one extremity of its movement, means operated by a return movement of the carriage for disengaging the latter from said detent, said disengaging means being operable when the rack is at predetermined points in its rotative movement, and means for normally holding 95 said disengaging means in operative relation with said detent. 90

6. An improvement in display racks comprising a reciprocable carriage, a rotatable carriage member supported thereby, a pivoted detent arranged to interrupt movement of said carriage near one extremity of its reciprocation, means attached to said rack member for disengaging said detent when the rack member is at predetermined 105 points in its rotative movement, said disengagement being effected by a movement of the carriage in one direction, and means for normally holding said disengaging means in operative relation with said detent. 110

7. An improvement in display racks comprising a reciprocable carriage, a rotatable rack member supported thereby, a pivoted detent arranged to interrupt movement of said carriage near one extremity of its reciprocation, a spring acting against said 115 detent, means attached to the rack member for engaging the free end of the detent to move the latter against the tension of its spring, said disengagement being effected by a movement of the carriage in one direction, said means being operable when the rack member is at predetermined points in its rotative movement.

8. An improvement in display racks comprising a reciprocable carriage, a rotatable rack member supported thereby, a pivoted detent arranged to interrupt movement of said carriage near one extremity of its reciprocation, said detent being provided with 125 130

an offset portion having a lug, a spring acting against said detent, means attached to said rack member for engaging said lug to move said detent when the rack member is 5 at predetermined points in its rotative movement, said engagement being effected by a movement of the carriage in one direction, and means for normally holding said engaging means in operative relation with 10 said detent.

9. As an improvement in display racks, a reciprocable carriage, a rotatable rack supported thereby, means for interrupting reciprocation of said carriage, said means 15 being located near one extremity of the movement of the carriage, a disk attached to said rack member, and means carried by said disk for disengaging said carriage from said locking means, said disengagement 20 being effected by a movement of the carriage in one direction, said disengaging means being operable at predetermined points in the rotative movement of the rack.

10. An improvement in display racks 25 comprising a reciprocable carriage, a rotatable rack member supported thereby, a pivoted detent arranged to interrupt movement of said carriage near one extremity of its reciprocation, a disk attached to said 30 rack member, and lugs carried by said disk for moving said detent to release said carriage, when the rack member is at predetermined points in its rotation, said lugs being brought into engagement with said detent 35 by a movement of the carriage in one direction.

11. An improvement in display racks

comprising a reciprocable carriage, a rotatable rack member supported thereby, a pivoted detent arranged to interrupt movement of said carriage near one extremity of its reciprocation, the free end of said detent being provided with a lug, and a disk attached to said rack member and provided with depending lugs arranged to engage the 45 lug of said detent to release the carriage at predetermined points in the rotative movement in the rack member, said lugs being brought into engagement with said detent by a movement of the carriage in one di- 50

12. As an improvement in display racks, a reciprocable carriage, a rotatable rack supported thereby, means for interrupting reciprocation of said carriage, said means 55 being located near one extremity of the movement of the carriage, a disk attached to the rack member and provided with means for disengaging the carriage from said locking means at predetermined points 60 in the rotative movement of the rack, said lugs being brought into engagement with said detent by a movement of the carriage in one direction, and means coöoperating with said disk to cause said rack member to assume said predetermined positions.

In testimony whereof I have hereunto set my hand in presence of two subscribing witnesses.
